PROCESS AND MEANS FOR PRODUCTION OF SURFACE IONIZATION IN INSULATOR BODIES

Arthur Johannes Krutzsch, Munich, Germany, assignor to International Precipitation Co., Los Angeles, Calif., a corporation of California

Application June 7, 1932, Serial No. 615,942
In Germany June 13, 1931

9 Claims. (Cl. 183—7)

This invention relates to a new process and new means for producing ionization parallel with the surface of insulating materials.

This ionization, which is manifested in the form of creeping sparks, polar brush discharges and the like, is hereinafter termed surface ionization. Surface ionization of this kind comes into consideration in dust precipitating plants for example, in which ionization is produced along the surface of a body composed of insulating material by means of a voltage, the carriers of electricity formed being withdrawn by another voltage from the ionization area and conveyed into the current of gas laden with dust or other substance where the particles held in suspension in the gas are then charged and precipitated.

The invention is also applicable in other branches, e. g. for chemical purposes, when it is desired to bring about chemical reactions between the layers on the surface of the body of insulating material and the surrounding gases under the action of electrical discharges or chemical decompositions within the gases or a mixture of gases. The discharges may also serve to clean insulation surfaces such for example as the surfaces of insulators.

Ionizing fields have been produced heretofore in systems provided with electrodes separated by an insulating layer. For instance, at the boundary of such a layer of insulating material a superficial ionization area is produced by supplying an alternating voltage to electrodes separated by an insulating layer, whereby electric fields are produced which partly pass in the dielectric and which partly pass on the surface of the insulating layer. By the employment of suitable voltages, so-called polar brushes or jump-over sparks are produced that alternately charge and discharge the sides of the insulator, that is, the insulating layer separating the electrodes. In this manner, the surface of the insulating layer is coated with an intense and uniform ionization layer. It has been shown that ionizers of this kind have an excellent ionization effect. This effect, however, is injured if the surface of the ionizer becomes coated with a layer of dust, moisture or like electrically conducting substances, since, in such an event, the electricity that would charge the sides of the insulating layer no longer passes as an ionizing current upon the insulating layer but as a simple conducted current within the layer of dust or the like. Externally, this difference becomes apparent in that the surface of the ionizer no

longer shows the presence of a luminous area indicating the presence of the ionizing current.

Now, when the ionizer becomes coated with dust and like conducting material, the situation is such that the ionizer includes two elements connected in series:

1. A resistance conductive dust layer formed upon the layer of insulating material.
2. A condenser-like system (the insulating layer between the conducting elements).

Thus, the entire voltage between the ionizer-electrodes is, in accordance with well known formulas, composed of the voltage along the resistance and of the voltage of the condenser.

Since the voltage of a condenser is proportional to the quantity of electricity present thereon, and the quantity of electricity is equal to the product of the strength of the current and the time, this leads to the conclusion that a great strength of field will arise in the aforementioned resistance (even if it be of great conductivity) where the voltage between the ionizing electrode increases very quickly for, in such an event, the quantity of electricity present on the condenser and at the same time the voltage of the condenser are so small that practically the entire voltage is present on the resistance.

Of course, this happens for only a short period of time, that is, only during the phase where the voltage rises steeply. If, therefore, the ionizer be fed with a voltage of rectangular shape for instance, a high field strength will develop on the ionizer surface for a short period of time, notwithstanding its conductivity. The field so produced, however, is sufficient for the production of ionization and in the operation of the system, in accordance with this invention, the dust covered surfaces again become luminous, showing the presence of a high ionization current.

To produce such steep fronts of the voltage waves means which are known per se may be employed.

In order to clearly describe the invention, reference is to be made to the following description and accompanying drawing in which:

Figs. 1, 2, and 3 show three wave forms of voltages considered in the invention for producing ionization.

Fig. 4 shows in a diagrammatic way a device in accordance with this invention.

Figs. 5 and 6 show in a diagrammatic way modifications of details of the arrangement of Fig. 4.

The ionizing circuit may be supplied with fluctuating voltage, whether it be an alternating current or a pulsating continuous current of rec-

tangular form (see Fig. 1 for example), trapeze form or stepped form (see Fig. 2 for example), which are produced by well known means, say in machines of a suitable type of construction or in 5 suitably controlled discharge tubes.

Particularly suitable as ionizing voltages, according to this invention, are those proceeding along a conductor with a steep front to the waves, that is, those waves termed travelling waves. 10 These travelling waves (like that shown in Fig. 3 for example) may be produced by impulses in switching, it being possible, by suitable arrangement and dimensioning of the electrical magnitudes of the circuit, the resistances, the 15 condensers, the self-induction of the windings or by supplementary apparatus, to determine the size and shape of the front of the wave, in accordance with the conditions, particularly the conductivity and kind of coatings or dusts which 20 are to be controlled.

An advantageous arrangement may be obtained if spark gaps be employed to produce impulses or breaks in the voltage and particularly such in which the spark is quenched by special 25 quenching devices, whether of an electrical, magnetic, electromagnetic or mechanical nature.

A constructional example of the invention is 30 illustrated in Fig. 4 of the drawing, which shows an ionizer for an electrical gas purifying plant, in which the strength of the field necessary for 35 ionization is produced in a section of space lying at the side of the charging area by means of a voltage and the charge carriers so formed conveyed by another voltage into the space charging area, the ionizing area being produced in particular superficially at the boundary of a layer of insulating material which separates the ionizing electrodes of the different polarities from each other.

40 The ionizer is denoted by 11. It consists in the example illustrated of a plate or insulating body 12 of insulating material, on both of the sides of which is arranged on the surface thereof or in the vicinity of the surface thereof, a series 45 of ionizing electrodes 13, 14, which consist of rod or strip shaped conductors of any kind of conducting material connected up in parallel with each other. In this example the two series are connected up in parallel with each other 50 and form one set of electrodes of the ionizer, while the opposite electrode is formed by a plate 15 of metal embedded in the plate of insulating material. An alternating voltage from the transformer 18 is supplied to the ionizer. The 55 charge carriers produced by the ionizer are conveyed by means of a further voltage into the space charging area which lies at the side of the ionizer, charge the particles of dust held in suspension there and are conveyed by means of the same voltage to the precipitating electrodes 60 20, 21. This voltage which serves to convey the charged particles to the precipitating electrodes is sent over the conductors 24, 25 to the precipitating electrodes connected up in parallel 65 therewith on the one hand and to the ionizer 11 on the other hand, and, in the example shown, as a continuous current, which is rectified out of the transformer by means of the rectifying tube 26. The condenser 30 which is connected 70 up in parallel with the electrodes of the continuous current, serves to smooth out the continuous current.

The ionizer 11 is constituted as a condenser-like system consisting of the insulating body

plate 12 any conducting coatings and conductors 13, 14, 15. An alternating voltage is supplied to the ionizer from the transformer 18 over the circuit 18, 36, 25, 14 (13), 15, 32, 37, 18. Separating plates or depositing electrodes, 20, 21, at which the dust or other matter in the gas to be purified, collects are fed by a different circuit 25, 14 (13), 21 (20), 24, 26 and is not influenced by the ionizer's operation. If dusts which conduct electricity or even those which conduct it 10 only slightly are present in the separating area, that is, the area between the ionizer and the separating plates, say soot for example, metal dust or even moist gases or gases which would otherwise affect the surfaces and make them 15 conductors, the surface of the plate 12 becomes coated with a layer thereof which conducts electricity more or less well. The voltage of the ionizer is then composed of the voltage along the resistance formed by the conducting layer of 20 the dust and the like and the voltage of the condenser-like system. Now the voltage of a condenser is proportional to the quantity of electricity which is present thereon, and this is equal to the product of the strength of the current and 25 the time. If the voltage supplied to the ionizer say by the spark gap 32 interpolated in the circuit for example, be selected in such a way that it rises rapidly with a steep front to the wave, there will be produced in view of the short time, 30 a low voltage at the condenser, so that practically the total voltage falls on the resistance formed by the coating.

If therefore the alternating voltage, alternating 35 current or pulsating continuous current supplied to the ionizer shows a steep front, there will be formed during the rapid variation in the voltage on the surface of the dust or other conducting layer, notwithstanding its comparatively high conductivity, for a short time, a very strong 40 electric field which will suffice to ionize the vicinity of the ionizer. Under the influence of the continuous voltage which prevails between the ionizer and the precipitating electrodes, charge carriers are withdrawn from the ionizing area, 45 the particles of dust or other particles held in suspension are charged and conveyed to the precipitating electrodes 20 and 21.

An ionizing voltage with as steep a rise and fall 50 of the voltage as possible will therefore be employed, which can be produced in any desired manner. If suitably built generators or tube rectifiers or even mechanical transformers like pendulum transformers for example, be used for the generation of the voltage with a steep front to the 55 wave, the circumstance must be taken into account that a flattening of the front of the wave is produced by the self induction of the transformer, by means of which the voltage is supplied as a rule to the ionizing circuit.

This flattening is avoided if the steep voltage front be produced directly in the ionizing circuit, which is possible by means of spark gaps for example. By means of the spark gaps those travelling waves will be generated and utilized which in general it is endeavoured to avoid in electric circuits. The sensitive parts such as transformers and the like can be protected against the action of the travelling waves in the usual way by protecting resistances 36, 37, 38. As the spark gap when suitably constructed only responds when the voltage at it has risen to a certain value, it acts in a manner of speaking as an automatic switch. As soon as the spark passes the resistance of the spark channel falls in a very short 70 75

time, about 10^{-7} seconds, to a low value. In accordance herewith the voltage in the ionizer varies in jerks, the jump in the voltage being more or less steep according to the conditions. By 5 suitably equalizing the capacity of the ionizer, the wave resistance, the length of the conductor from the spark gap to the ionizer, the size of the protecting resistances, the leakage from the transformer and the like and by inserting appropriate 10 apparatus, such for example as connecting the condenser (40) in parallel with the transformer 18, it is possible to control the steepness of the rise in the voltage, particularly when the capacity of the condenser 40 is large as compared with the 15 capacity of the ionizer.

The spark gap will therefore be so constructed that its capacity is small. If, however, the capacity of the ionizer is exceptionally small, it will be of advantage to even connect, in addition and 20 parallel to the spark gap, a small capacity, as the final resistance of the spark is, as is well known, inversely proportional to the quantity of the electricity which passes through it.

In order to obtain a rapid collapse of the 25 resistance of the spark and to prevent a current from flowing between the spark gap electrodes before the spark proper passes, the arrangement will be so devised that the spark passes directly from the so-called initial voltage and that no 30 glow, brush discharge or the like takes place before the spark. Only a comparatively slight curvature is therefore given to the electrodes of the spark gap. Care is also taken that the sparks which follow each other in accordance with the 35 change in the voltage of the ionizer shall not meet many ions in the spark gap from the sparks which precede in each case and consequently pass even at slight amplitudes of the voltage or under some circumstances persist even as arcs or arc 40 discharges or the like. For this purpose the electrodes of the spark gap may be specially constructed for example with cooling ribs or may be made of a special material of high thermal conductivity for example. The electrodes may also 45 be cooled or the spark allowed to pass in a special medium (such as gas under high pressure, oil or other dielectric liquid or the like). For this purpose suitable quenching devices of an electric, magnetic or electromagnetic nature may be pro- 50 vided at the spark gap, such as are used for example for preventing arcs from being struck when switches are operated. For this purpose also the spark gaps or parts thereof may be made to move or the electrodes may be subjected to a blast. A 55 favourable effect is produced if the axis of the spark gap be horizontal as by this means the upward thrust of the heated air produced at the spark gap acts of itself to regenerate the spark gap. It is particularly favourable for this purpose 60 to give the electrodes a considerable amount of curvature, but such curvature must not be so great that glowing or discharges are formed before the spark passes.

A valuable constructional form of the idea on 65 which this invention is based results if one or both of the electrodes of the spark gap be made hollow and the surface provided with one or more openings at the place where the spark is produced, see 45, Fig. 5. By means of a suitable apparatus such as a motor 46 for example a pump 70 47, pipes 48 a fluid medium either liquid or gaseous under a head of pressure is then supplied to the spark gap or compressed air for example or an inert gas under pressure, such as nitrogen for 75 example, is supplied or the medium may be with-

drawn by the creation of a vacuum away from the spark gap through the opening 45, the pipes 48 or pumping apparatus 46, 47.

Instead of one spark gap a number of spark gaps may be connected up in series in a suitable form in order to obtain great steepness in the jump in the voltage. In like manner and for the same purpose the conductors of the ionizer may be composed of pieces of conductors with different travelling wave resistances. The voltage may also be intensified by the reflection of the travelling waves at the ionizer and particularly when a long conductor or a number of sections of conductors of definitely graduated wave resistances are interposed between spark gaps. 10 15

As the condenser 40 means a high capacitative load on the transformer 18 and the plant it is possible in order to reduce the loading current and to equalize the capacitative load of the plant to use a self-induction coil 50 (see Fig. 6) which may be interposed at a suitable point for example in parallel with the secondary winding of the transformer 18. The magnitude of the self-induction may conveniently be such that together with the total capacity of the loading circuit resonance for the primary or basic wave of the primary alternating current is produced. 20 25

In the present invention the spark gap does not serve to produce high frequency damped oscillations as is well known per se, but on the contrary the spark gaps are intended to serve like the other arrangements described to produce the special form of voltage and steep alternation in the voltage. Whether in addition thereto high frequency waves are produced by the spark gaps is of no consequence as far as this invention is concerned as the important point is the action of the special form of voltage. Since furthermore the self-induction of the ionizing circuit is kept as small as possible so as not to flatten the rise in the voltage, the high frequency oscillation which will be produced in any case will be of a magnitude which may be neglected. 30 35 40

It will be understood that the invention is not limited to the embodiments described and illustrated by way of example and that various structural changes and modifications may be made without departing from the spirit of my invention, and I desire therefore that the appended claims should be construed in the light of prior knowledge. 45 50

It will be understood that the term "alternating voltage with a steep rise and fall of the voltage" includes alternating voltages having steep fronts to the wave as for instance the rectangular, stepped and trapeze forms illustrated in Figs. 1, 2 and 3 rather than the usual sinuous form of alternating current wave. 55 60

Having thus described my invention, what I claim as new and desire to secure by Letters Patent, is:—

1. An ionizing device comprising spaced ionizing electrode members, a body of insulating material separating said members, a source of high voltage current, and means connecting said source with said ionizing electrode members to produce a high potential therebetween, said connecting means including means for supplying said voltage in short impulses of steep wave front. 65 70

2. An ionizing device comprising a body of insulating material, an ionizing electrode member positioned at the surface of said body and a 75

5 further ionizing electrode member spaced from said first ionizing electrode member and separated therefrom by said body, a source of high voltage current, and means connecting said source with said ionizing electrode members to produce a high potential therebetween, said connecting means including means for supplying said voltage in short impulses of steep wave front.

10 3. An ionizing device comprising a body of insulating material, an ionizing electrode member positioned at the surface of said body and a further ionizing electrode member in contact with said body and separated thereby from the first ionizing electrode member, a source of high voltage current, and means connecting said source with said ionizing electrode members to produce a high potential therebetween, said connecting means including means for supplying said voltage in short impulses of steep wave front.

15 4. An ionizing device comprising a body of insulating material, an ionizing electrode member positioned at the surface of said body and a further ionizing electrode member embedded in said body and separated thereby from the first ionizing electrode member, a source of high voltage current, and means connecting said source with said ionizing electrode members to produce a high potential therebetween, said connecting means including means for supplying said voltage in short impulses of steep wave front.

20 5. An ionizing device comprising spaced ionizing electrode members, a body of insulating material separating said members, a source of high voltage current, and means connecting said source with said ionizing electrode members to produce a high potential therebetween, said connecting means including a spark gap for supplying said voltage in short impulses of steep wave front.

25 6. In an electrical precipitator, an ionizing device comprising spaced ionizing electrode members, a body of insulating material separating said members, a source of high voltage current, means connecting said source with said ionizing electrode members to produce a high potential therebetween, said connecting means including means for supplying said voltage in short impulses of steep wave front, a collecting electrode

member spaced from said ionizing device, means for producing a high potential between said ionizing device and the collecting electrode member, and means for passing a fluid between at least one of said ionizing electrode members and the collecting electrode member. 5

7. In an electrical precipitator, an ionizing device comprising a body of insulating material, an ionizing electrode member positioned at the surface of said body and a further ionizing electrode member spaced from said first ionizing electrode member and separated therefrom by said body, a source of high voltage current, means connecting said source with said ionizing electrode members to produce a high potential therebetween, said connecting means including means for supplying said voltage in short impulses of steep wave front, a collecting electrode member spaced from said ionizing device, means for producing a high potential between said ionizing device and the collecting electrode member, and means for passing a fluid between at least one of said ionizing electrode members and the collecting electrode member. 10 15

8. Method of producing ionization at the surface of a body of insulating material in contact with spaced electrode members which comprises providing a high potential electric field between said spaced electrode members and maintaining a relatively high drop in voltage along the surface of said body by impressing short impulses of steep wave front across said spaced electrode members. 20 25

9. Method of electrically precipitating suspended material from fluids which comprises passing a stream of fluid between a collecting electrode and a body of insulating material in contact with spaced electrode members, producing ionization at the surface of the body of insulating material by providing a high potential electrical field between said spaced electrode members, maintaining a relatively high drop in voltage along the surface of said body by impressing short impulses of steep wave front across said spaced electrode members, and providing a high voltage electrical field between at least one of said spaced electrode members and said collecting electrode. 30 35 40 45
